US00D907629S

(12) **United States Design Patent** (10) **Patent No.:** **US D907,629 S**
Mitchell (45) **Date of Patent:** **** Jan. 12, 2021**

(54) **COORDINATE INPUT DEVICE**

- (71) Applicant: **Wacom Co., Ltd.**, Kazo (JP)
(72) Inventor: **Giles Thomas Mitchell**, Toyko (JP)
(73) Assignee: **Wacom Co., Ltd.**, Kazo (JP)
(**) Term: **15 Years**
(21) Appl. No.: **29/639,212**
(22) Filed: **Mar. 5, 2018**

Related U.S. Application Data

- (63) Continuation of application No. 29/601,739, filed on Apr. 25, 2017, now Pat. No. Des. 812,050.

Foreign Application Priority Data

- Dec. 21, 2016 (JP) 2016-027749

- (51) **LOC (13) Cl.** **14-02**
(52) **U.S. Cl.** **USPC** **D14/341**

Field of Classification Search

- USPC ..... D14/315-318, 341-347, 420, 426, 240, D14/129-130, 496, 137, 138 R, 138 AA, D14/138 AB, 138 AC, 138 AD, 138 C, D14/138 G, 147, 203.1-203.8, 218, 247, D14/371, 248, 388-389, 374; D6/308, D6/310; D10/104.1, 50, 65; D18/6-7; D19/26, 59, 60; D21/324, 329, 330, 332 CPC G06F 1/1626; G06F 1/1613; G06F 3/0488; G06F 3/04886; G06F 3/041; G06F 3/0412; G06F 3/0416; H04M 1/725; H04M 1/0202; H04M 1/0266

(57) CLAIM

The ornamental design for a coordinate input device, as shown and described.

DESCRIPTION

FIG. 1 is a front bottom left perspective view of a coordinate input device according to my new design;

FIG. 2 is a rear top right view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The dashed broken lines in the drawings show portions of the coordinate input device that form no part of the claimed design.
